CIGARETTE TOBACCO FEED

James W. Warren, Lynbrook, N. Y., assignor to
 American Machine & Foundry Company, a corporation of New Jersey

Application March 26, 1938, Serial No. 198,277

6 Claims. (Cl. 131—109)

This invention relates to a tobacco feed for a continuous rod cigarette machine, especially for a machine of the type in which shredded tobacco supplied from a mass thereof in a hopper is fed between a "bottom feed drum" and a refuser drum in a stream which follows a path extending downwardly through a comb and a picker roll to a rotatable winnower which is run at relatively high speed to gather the tobacco and hurl it through different trajectories, thus separating the desired shreds of tobacco from undesirably heavy pieces, stems and foreign matter which may be contained within the tobacco mass.

The shower of tobacco in desired shreds falls progressively in a mat upon a surface on which it is advanced to a feed couple, such a surface being preferably the travelling surface of an endless conveyor, as for example, an endless belt or conveyor apron by which it is delivered to the aforesaid feed couple, and is fed thereby in the form of another shower to the strip of wrapper web, and is there formed into a rod.

The operation of machines of this type has been subject to the disadvantage that a gap existed between the path followed by the blades of the rotary winnower and path of the mat formed on the collecting surface by the shower of desired shreds from the winnower, and this gap permitted the passage therethrough of air currents which blew the shredded components of the shower in various directions, resulting in the formation of a mat characterized by uneven thickness and containing ridges and intervening depressions which were represented in the rod by hard spots and soft spots. When a rod of this uneven formation is severed at a soft spot, the result is to turn out two cigarettes each having loose tobacco in the ends at which they adjoin each other prior to severance. The existence of loose tobacco at the end placed in the mouth of a smoker is objectionable for well-known reasons, and if a like condition exists at the end to be lighted, it is objectionable for equally well-known reasons. Accordingly, many rejects are due to the cause above described. Of course, the existence of either a soft spot or a hard spot at any portion of a cigarette has its characteristic disadvantages, to be obviated if possible.

Under such conditions, the primary object of the present invention is to provide means to avoid the occurrence of air currents capable of producing the defects above described, and in pursuance of the above general object, it is an object of the invention to so arrange the winnower, its arcuate bottom concave, and the

stretch of surface on which the shower from the winnower descends, that there will be no such gap through which an air current can find access to the shower. A cognate object is to so arrange the arcuate concave that its lengthwise dimension, crosswise of the hopper, will bring the ends of the arcuate concave into close relation with the side walls of the hopper, in order to prevent the passage of air through crevices at such regions also, and the disturbance of the shower at these points. Accordingly, when this invention is carried into effect, the shower will form an even mat of uniform thickness upon the collecting surface and thus the rod fabricated in the rod-former will be substantially freed from the occurrence of soft or hard spots, so far as they have been due to the cause above described, and more perfect cigarettes will therefore be produced.

Other objects and features of the invention will appear as the description of the particular physical embodiment thereof selected for description progresses.

The accompanying drawing is a view of a somewhat schematic character, in sectional elevation, of part of a tobacco feed in the construction of which the present invention has been embodied.

In the now preferred embodiment of the invention thus selected for illustration, the automatic tobacco feed mechanism shown comprises a tobacco hopper 5, a "bottom feed" drum 6, a refuser drum 7, a comb 8, a picker-feed drum roll 9, a feeding apron or conveyor belt 10, a collecting apron or surface 11, a filler roll couple 12—13, 30 a picker roll 14 and a chute 15, all constructed and cooperating to deliver the final shower W of desired shreds to the web P of wrapper paper preparatory to formation of the rod, in a manner well-known in the art and therefore requiring no detailed description, other than that incidental to the following specification.

Provision is also made of a winnowing device of substantially conventional form, which comprises a rapidly rotating shaft or member 16, 45 adjacent to the feed drum 6, and carrying a fixed core 17 formed with spaced apart blades 18, in somewhat radial disposition, which gather the stream of tobacco shred T issuing from the drum 6 and picker 9, the winnower hurling the stream 50 through different trajectories, determined by the differences in mass of the individual shreds. In operation, the desirable lighter shreds S will fall upon the forwarding apron 11, while the undesirable heavier pieces of stem and foreign mat- 55

ter F will be hurled into a receptacle 19, this receptacle taking preferably the form of a drawer which may be withdrawn from time to time to permit removal of the collected contents. The 5 showing of a winnower formed separately from the picker roll 9 is not intended to exclude the provision of picking means on the winnower itself or otherwise cooperating therewith.

In pursuance of the invention, the apron 11 is 10 arranged with the rear end of its collecting surface in close proximity to an arcuate concave 20, which terminates at its lower end in closely arranged disposition with relation to the path of the winnower blades 18, extending upward therefrom to the point 21 which defines the nearest approach of the blades 18 to the feed drum 6.

The contact of the concave 20 with the apron 11 makes a seal which serves to prevent air currents from passing therethrough, and the length 20 of the arcuate concave is preferably equal to the breadth of the hopper 5, so that no gaps for passage of air will be left between the winnower and the adjacent walls 5 of the hopper. This contact of the concave with the apron tends to remove 25 any tobacco dust which may accumulate on the edge of the lower end of the concave. Otherwise the tobacco dust accumulating at this point may occasionally drop off upon the apron and form non-uniform spots in the cigarette rod.

Accordingly, the desired shreds S of winnowed 30 tobacco descend evenly upon the apron 11, forming thereon an even mat of desired tobacco shreds having a uniform thickness, and which are delivered smoothly through the feed couple 12-13 35 and the picker roll 14 to and through the chute 15, into the trough P forming part of the rod-former of a cigarette machine.

In order to prevent short tobacco from leaking 40 from the hopper at point 25 and also from passing between the winnower and the drum 6 onto the collecting surface 11, the concaves are extended up and around the winnower 18 to a point 24 and then around the drum 6 to the point 25. This prevents the delivery to the mat of any uncontrolled masses of shorts.

There may be considerable variation in the 50 structure of the concave element by which this feature of the present invention is put into practice, and in the instance illustrated the concave 20 is attached to a band 22 receiving one end of an adjusting screw 23, carried by a cross-bar 24 on the feed frame, and which provides means for the adjustment of the concave in a vertical direction so as to maintain the desired contacting 55 pressure of the ends of the concave with the aprons. An extension 26 of the concave 20 is so placed within the hopper that its end 25 also acts to prevent air leakage. The cooperation of the collecting surface 11 with the rotating blades 60 18 is such also that any desired shreds which may be carried downward and rearward by the blades 18 of the winnower will be cleared therefrom by the forward movement of the surface 11, which acts as a "doctor" for the winnower.

65 What is claimed is:

1. A tobacco feed comprising a winnower, means to feed a stream of shredded tobacco from a supply thereof to said winnower, which is rotatable in the path of said stream in a direction to 70 intercept said stream of tobacco and impel the particles of tobacco over the top of the winnower and away from said stream, a concave element having an arcuate face extending around a substantial arc of the lower circumference of said 75 rotary winnower at the side thereof adjacent said

means and in close proximity to the periphery of said winnower, and a conveyor having an endless travelling surface adapted to receive a shower of desired shreds from said winnower, said conveyor being disposed with its working surface in tangent relation with the lower surface of said arcuate concave to exclude the passage of air currents between the concave and conveyor, and thereby to promote the showering of said tobacco onto said conveyor by said winnower in a mat of substantially uniform thickness. 5

2. A tobacco feed comprising a winnower, means to feed a stream of shredded tobacco from a supply thereof to the winnower, which is rotatable in the path of said stream in a direction to intercept said stream of tobacco and impel the particles of tobacco up over the top of the winnower and away from said stream, and a concave element having an arcuate face extending around a substantial arc of the lower circumference of said rotary winnower, and a conveyor apron having an endless travelling surface adapted to receive a shower of desired shreds from said winnower. 15

3. A tobacco feed comprising a winnower, means to feed a stream of shredded tobacco from a supply thereof to said winnower, which is rotatable in the path of said stream, a concave element having an arcuate face extending around a substantial arc of the lower circumference of said rotary winnower, and a conveyor having an endless travelling surface adapted to receive a shower of desired shreds from said winnower, 30

35

4. A tobacco feed for a continuous rod cigarette machine comprising in combination a hopper for containing a mass of shredded tobacco, a bottom feed drum, a conveyor having a tobacco feeding surface extending under and travelling toward the bottom of said feed drum for advancing there-to shredded tobacco, means to rotate said feed drum to elevate shreds received from said conveyor, a refuser drum coating with said feed drum to regulate the feeding of a stream of said shredded tobacco around the top of said feed drum and under said refuser drum, a picker roll 40 cooperating to loosen the tobacco in said stream thereof, as it travels downward from between said drums, a winnower rotatable in the downward path of said loose stream, a bottom concave element having two merging arcuate portions 50 concentric with said winnower and bottom drum extending from a plane substantially defined by the axes of rotation of said winnower and said bottom drum, the portion concentric with the lower drum extending into tangent relationship to said conveyor; and a conveyor apron having an endless travelling surface adapted to receive a shower of desired shreds from said winnower, 55

ject to disturbing air currents from a source beyond the hopper.

5. A tobacco feed comprising a winnower, means to feed a stream of shredded tobacco from a supply thereof to said winnower, which is rotatable in the path of said stream, a concave element having an arcuate face extending around a substantial arc of the lower circumference of said rotary winnower, a conveyor apron having an 10 endless traveling surface adapted to receive a shower of desired shreds from said winnower, means to maintain said concave in position to exclude the passage of air currents between the concave and conveyor, said feeding means including a feed drum, and a concave element extending beneath the lower circumference of said feed drum and meeting the first named concave

adjacent to the region of nearest approach of the peripheries of the winnower and feed drum to each other, said arcuate concaves being constituted by integral divergent faces of a unitary element.

5
6. A tobacco feed comprising a winnower, mechanism to feed a stream of shredded tobacco from a supply thereof to said winnower which is rotatable in the path of said stream, and a conveyor having an endless traveling collecting surface adapted to receive a shower of desired shreds from said winnower, and means to prevent any air currents between the winnower and said collecting surface other than those entrained within 10 the circumference of the winnower. 15
